PRINTING MACHINE

Walter T. Gollwitzer, Chicago, Ill., assignor to
Addressograph Company, Chicago, Ill., a cor-
poration of Delaware

Application November 22, 1930, Serial No. 497,440

20 Claims. (Cl. 101—47)

This invention relates to printing machines and more particularly to a machine through which variable printing devices are sequentially passed and in which impressions are made at various positions on sheets successively fed thereinto.

My invention is particularly useful in connection with printing machines used in the printing of tax bills, especially for real property. The legal description of parcels of property is printed on the tax bills, and this legal description is often of such a length that it cannot be arranged on but a single printing device, and it is therefore arranged on a number of printing devices which are collected in groups and the sheet is moved in the machine so that impressions will be made thereon from each of the printing devices of a group. Furthermore, the tax bill may embody one, two, or three sections, and impressions are made from each of the printing devices on each of the sections. It is manifest that the sheets are not uniformly passed through the machine, for when the legal description is on but a single printing device and the tax bill has two sections there will be only two impressions made on the tax bill, but when the legal description is arranged on two printing devices four impressions will be made on the bill. It is therefore the salient object of my invention to provide a novel arrangement for feeding the bills or sheets into a printing machine so operable that a new sheet will not be fed into the machine until all of the impressions have been made on the previously fed sheet.

Another object is to provide a pneumatically operated device for separating the sheets from the stack in which they are arranged and to successively feed them one by one into the machine. And an ancillary object is to so control the pneumatic devices that inadvertent operation will not occur.

A further object of the invention is to provide a safety device which will interrupt operation of the machine in the event no sheet is fed thereinto.

A still further object of the invention is to provide a device of the above described character which may be electrically controlled in order that rapid and positive operation thereof will be assured.

In the accompanying drawings a selected embodiment of the invention is illustrated and therein

Fig. 1 is a top plan view of a typical printing machine with which my invention is associated;

Fig. 2 is a fragmentary sectional view taken substantially on the line 2—2 on Fig. 1;

Fig. 3 is a fragmentary detail view taken substantially on the line 3—3 on Fig. 1;

Fig. 4 is a perspective detail view of the device as illustrated in Fig. 3;

Fig. 5 is a fragmentary elevational detail view

looking in at the right hand end of the device as illustrated in Fig. 1;

Fig. 6 is a sectional view taken substantially on the line 6—6 on Fig. 5, in which certain parts are broken away;

Fig. 7 is a fragmentary sectional view taken substantially on the line 7—7 on Fig. 1;

Fig. 8 is a fragmentary detail view similar to Fig. 7, showing the parts in another position;

Fig. 9 is a fragmentary detail view taken substantially on the line 9—9 on Fig. 1;

Fig. 10 is a sectional view taken substantially on the line 10—10 on Fig. 1;

Fig. 11 is a sectional detail view illustrating the operating parts in a position advanced from that shown in Fig. 6;

Fig. 12 is a transverse sectional view of the machine illustrating a switch arrangement employed to control operation of the sheet feeding device;

Fig. 13 is a diagrammatic view illustrating the electrical connections;

Fig. 14 is a detail view of the main clutch;

Fig. 15 is a vertical sectional detail view showing the platen operating and printing device feeding means operating means;

Fig. 16 is a vertical sectional detail view illustrating the selector operating means and the means for moving the printing devices through the printing device guideway;

Fig. 17 is a perspective view illustrating the sheet moving devices arranged on the top of the table of the machine; and

Fig. 18 is a detail view of the devices operating the sheet shifting mechanisms.

In the accompanying drawings wherein a selected embodiment of my novel sheet feeding device is illustrated in connection with a printing machine, 12 indicates the frame of the machine having thereon a bed 13 supporting a table top 14 over which the tax bills or other sheets to be printed are passed. On this table top 14 is a jogger pan 15 into which the sheet is carried by a belt 16 or other suitable sheet moving device. The machine includes a magazine M into which the printing devices D are introduced and from which they are sequentially withdrawn and passed along the usual printing device guideway G into printing position below the platen P operable from the shaft 17 in the manner described in my co-pending application, Serial No. 497,438 filed in the United States Patent Office on November 22, 1930.

In Figs. 15 and 16 the devices, disclosed in my referred to co-pending application, for operating the platen are illustrated and by referring thereto it may be seen that the platen arm 130 includes a leg 131 pivotally mounted on a lug 132 mounted on the bed 13. Branch arms 133 and 134 are provided on the platen arm and are ex-

tended on opposite sides of the shaft 17 and respectively mounted thereon are rollers 135 and 136 respectively engaging conjugated cams 137 and 138 mounted on a sleeve 139 disposed about the shaft 17 and detachably connected thereto to be under control of the selector mechanism disclosed in my referred to application, Serial No. 497,438. When the sleeve 139 is connected to the shaft 17 to rotate therewith, the conjugated cams 10 act on the rollers 135 and 136 and impart a rocking movement to the platen arm 130 to thereby move the platen P mounted on this arm toward and away from the printing device in printing position in the printing device guideway and 15 which printing position is located immediately below said platen P.

The printing devices are moved from the magazine M into printing position and are discharged from printing position by pawls 140 on the printing device feeding chains 141 mounted at opposite sides of the printing device guideway G. The printing device feeding chains extend about sprockets, such as 142, (Fig. 16) and a step by step movement is imparted to these sprockets and 25 to the chains 141 from a rocker 143 pivotally mounted at 144 on the bed 13. The rocker 143 has a pawl 145 at the outer free end thereof having a recessed nose 146 adapted to successively engage the pins 147 on the sprocket 142 when a 30 reciprocal movement is imparted to the rocker 143. The reciprocal movement is imparted to the rocker 143 from an eccentric 148 mounted on the shaft 17 and surrounded by a band 149 carrying a plunger 150 that is extended through a 35 sleeve 151 that is fast on an arm 152 which is a continuation of the rocker 143. A collar 153 is fast on the plunger 150 and is engaged by the shoulder 154 on the latch 155 that is pivotally mounted at 156 on the sleeve 151. So long as 40 the shoulder 154 rests on the collar 153 and a reciprocal movement is imparted to the plunger 150 by the eccentric 148 an oscillatory movement is imparted to the rocker 143. However, a pin 151 is provided on the latch 155 and 45 this pin is engageable with a cam surface 158 on the rocker 159 that is pivotally mounted at 160 and which has an arm 161 carrying a roller 162 engageable with a cam 163 on the cam shaft 32 to be described more fully hereinafter. So long 50 as the roller 162 rides on the rise or dwell of the cam 163, the rocker 159 is so positioned that the cam surface 158 will be engaged by the pin 157 in the reciprocation of the plunger 150 and the shoulder 154 will be disengaged from the collar 55 153 and no reciprocal movement will be imparted to the rocker 153 with the result that feeding of the printing devices through the printing device guideway will not occur. However, when the roller 162 moves onto the drop 164 of the 60 cam 163, the cam surface 158 is retracted from the line of movement of the pin 157 and therefore the shoulder 154 will engage the collar 153 and reciprocal movement will be imparted to the rocker 143 which will effect a step in the step by 65 step movement of the printing device feeding chains 141 each time the nose of the pawl 145 engages a pin 147. The sheet moved into the jogger pan 15 by the belt 16 is moved relative to the platen P by the belt 16, pan 15, and sheet jogging roller 18 in the manner described in my co-pending application, Serial No. 497,439, filed 70 in the United States Patent Office on November 22, 1930.

The sheet feeding device forming the subject 75 matter of this invention successively passes sheets

onto the belt 16 in timed relation with the operation of the machine. The movement of the sheet relative to the platen P after it passes onto the belt 16 is controlled by the mechanism fully described in my referred to co-pending application, Serial No. 497,439 and which mechanism is illustrated in Figs. 17 and 18.

As shown in Fig. 17, the belt 16 is directed across the pan 15 mounted on the table 14, as stated. This pan 15 has lugs 165 depending therefrom which pass through slots in the table top 14 and which extend therethrough at right angles to the extent of the belt 16 and these lugs are movable along these slots to permit shifting of the pan 15 relative to the belt 16.

Shifting of the pan 15 is controlled by tabs or other identifying means provided on the printing devices which are engaged by detectors to close an electric circuit at a predetermined time, as described fully in my referred to co-pending application, Serial No. 497,439. Included in the electric circuit just referred to is the solenoid 166 and just prior to the time that the circuit is closed to this solenoid the rise on the cam 164' on the platen operating shaft 17 engages the 25 roller 165' at the upper end of the operating lever 166' that is pivotally mounted at 167 on a bracket 168' extending upwardly from the bed 13. Pivotally connected to the lower end of the lever 166' is a pawl 168 having a pin 169 depending therefrom. Joined to the operating lever 166' is a latch 171 having a shoulder 172 thereon which normally rests against the flat portion of the half-round pin 173 mounted on the member 174 which supports the solenoid 166. As soon as the rise on the cam 164' engages the roller 165' the lever 166' is so moved that the end thereof connected to the pawl 168 moves in a counter-clockwise direction, as viewed in Fig. 18, and therefore the shoulder 172 is moved a short distance to be disengaged from the flat portion on the pin 173. Simultaneously with this, circuit is closed to the solenoid 166 to move the armature 175 thereof upwardly.

Disposed in alignment with the upper end of the armature 175 is a pin 176 carried by the latch 171 and since the shoulder on the latch will have previously been disengaged from the flat portion on the pin 173, the latch may be moved upwardly in an amount sufficient to disengage the shoulder 172 from the flat portion. A spring 177 extends between spring anchors on the lever 166' and the member 174 and as the cam 164' continues to move and as the rise on said cam is withdrawn from engagement with the roller 165', the spring 177 acts on the lever 166' to hold said lever in engagement with the periphery of the cam 164' and therefore the lever is motivated to move the pawl 168 toward the left, as viewed in Fig. 18. The pawl 168 has a spring anchor at one end thereof to which one end of a spring 179 is attached, the other end of said spring being connected to a spring anchor on the lever 166'. The disengaging of the shoulder 172 from the flat portion 173 and the movement imparted to the lever 166' by the spring 167 causes the latch 171 and the pawl 168 to be moved toward the left, as viewed in Fig. 18, and when the pawl 168 is so moved the spring 179 pivots said pawl. On the end of the pawl 168 opposite the spring anchor thereon is a pin 181 having a half-round portion thereon.

Slidably supported below the bed 127 is a rack 182 having a plurality of ratchet teeth 183 thereon. When the pawl 168 starts to move in the

above described manner and when it is pivoted by the spring 179, the flat portion on the pin 181 engages the first of the ratchet teeth 183 and the rack 182 is moved with the lever 166'. A retaining pawl 183' is provided which includes a pin 184 having a half-round portion thereon and this retaining pin is pivotally mounted below a shoulder on the block 166 and includes a relieved upper surface. Disposed between this relieved upper surface and the upper portion of the block is a spring 188 which normally urges the half-round portion of the pin 184 into engagement with the ratchet teeth 183. The movement imparted to the rack 182 by the pawl 168 is sufficient to move the rack the length of one tooth in order that the flat portion of the pin 184 will be forced into engagement with the tooth subsequent to the tooth it has been engaging.

The block 165 is secured to a rack 190 and the gear teeth in this rack mesh with a pinion 191 on the shaft 192 and which carries a similar pinion meshing with a rack on a block similar to the block 165. The jogger pan 15 is connected to the blocks and when the pawl 168 moves the rack 182, as described, the jogger pan 15 is moved rearwardly toward the platen P. The pan includes channel portions 198 and 199 between which the sheet moved by the belt is received. An opening 197' is provided in the pan which is aligned with the printing device opening in the table top 14. Hence when the pan 15 is moved in the above described manner, a sheet received between the channel portions thereon is moved transversely of the line of movement imparted to the sheet by the belt 16.

In the operation of the machine the sheet is sometimes moved in the direction opposite to that in which it is moved by the belt 16 and it is to accomplish this that the sheet jogging roller 18 is provided, and this roller is mounted on the free end of a flexible shaft 203 which is journaled in a bearing 202 carried by the channel portion 199. The opposite end of the shaft 203 is journaled in a bearing in the bracket 205 and at this end of the shaft there is a bevel gear 206 which meshes with a bevel gear 207 on the shaft 40. Inasmuch as the shaft 40 is continually rotated, it is manifest that the roller 18 is continually rotated. Therefore, the roller 18 is held from engagement with the sheet in the pan 15 and this is accomplished by the arm 208 of the bell crank, generally indicated by 209, which is pivotally mounted in a bracket 210. Connected to the arm 217 of the bell crank 209 is a link 218 which is adjustably attached to the lever 166'. When the lever 166' is moved by the spring 177 the link 218 is moved toward the left, as viewed in Fig. 18, and the bell crank 209 is so moved that the arm 208 thereof moves in a counter-clockwise direction, as viewed in Fig. 17, and it is therefore drawn from engagement with the rocker 201 on which the bearing 202 is carried, and this permits the roller 18 to move into engagement with the sheet and this engagement of the roller with the sheet causes the sheet to be moved in a direction opposite to that in which it is moved by its engagement with the belt 16.

To insure movement of the sheet with the belt 16 I provide a roller 215 mounted on an arm 216 pivotally mounted on a shaft 217. The arm 216 includes a portion engageable with the cam 218 on the cam shaft 38 and this cam acts to raise and lower the roller 215, as will be described. Movement of the sheet is arrested, to permit impressions to be made thereon by the platen P, by

stop fingers 219 and 220 respectively mounted on arms 221 and 222 having parts respectively engaging the cams 223 and 224 on the cam shaft 38.

In the operation of the machine, the cam shaft 38 rotates and at a predetermined time the cam 223 thereon moves the stop finger 219 into position to engage the forward edge of the sheet and at this same time the cam 218 acts to retract the roller 215 from engagement with the sheet and when the forward end of the sheet engages the stop finger 219 movement of the sheet is arrested and the platen P acts to make an impression thereon. The cam 223 then retracts the stop finger 219 and the sheet again starts to move with the belt 16 and this movement is aided by the roller 225 similar to and controlled similar to the roller 215. When the sheet is so moving, the cam 224 acts to position the stop finger 220 in position to engage the sheet and immediately prior to this engagement the roller 215 is retracted. The platen P then makes an impression on the sheet in the pan 15.

Now if but two impressions are to be made on the sheet the stop finger 220 is retracted and the belt 16 carries the sheet from the machine. However, if additional impressions are to be made, the pan 15 is shifted, as described, and the roller 18 moves the sheet rearwardly whereupon the sheet again moves into engagement successively with the stop fingers 219 and 220, and this operation may be continued until as many impressions as desired have been made on the sheet.

The pan 15 is repositioned after it has been moved by the closing of a circuit to the solenoid 223, the arm 227 of which has a link 228 connected thereto that controls the operation of the retaining pawl 184, and when the solenoid 226 is energized the retaining pawl is retracted whereupon the spring 229 moves the pan 15 back into its initial position.

When the machine is used in the printing of tax bills for real property the printing devices D have thereon the name and address of the owner of a parcel of real property as well as the legal description of the property. These printing devices are successively withdrawn from the magazine M and are passed through the machine below the platen P which makes impressions therefrom through a suitable ink ribbon in the manner well understood in the art. The legal description of the parcels of property can sometimes be arranged on but a single printing device, but is often arranged on two or more printing devices, and the machine is so arranged that printing operations will be performed on each tax bill in accordance with the number of printing devices having the legal description of the particular parcel of property for which the tax bill is being printed. Furthermore, the tax bill often has more than one section, as for example, two sections and impressions are made from each of the printing devices on each of the sections of the tax bill. If, for example, the legal description is arranged on two printing devices and the tax bill has two sections the bill will be moved into position below the platen P and impressions will be made from the first printing device on the first section thereof and an impression will next be made from the first printing device on the second section thereof. The sheet will then be moved laterally and transversely of the machine to align the portion thereof below that receiving the first impression with the platen, and the printing devices will be changed during the time the sheet is being shifted

70
75
80
85
90
95

and an impression will be made from the second printing device on the first section of the bill and after this has been performed the bill will be moved to receive an impression from the second printing device on the second section of the bill. If the sheet has more sections or if the legal description is arranged on more than two printing devices the sheet will be additionally moved, as described above and with particularity in my referred to copending application, Serial No. 497,439.

Sometimes the legal description is arranged on but one printing device and therefore the number of impressions made on the tax bill will be equal to the number of sections thereof which in this instance is two. Thus, a sheet will be withdrawn from the rack on which it is stored, passed into the machine to receive the two impressions, and be passed therefrom. Manifestly, this will be performed much more rapidly than when a sheet is withdrawn from the rack, passed into the machine to receive four impressions, after which it is passed from the machine, and clearly four impressions can be made much more rapidly than six impressions. Therefore, the sheet feeding device is operated in timed relation with the movement of the sheet being printed and a new sheet will not be passed into the machine until the time the last impression is being made on the preceding sheet.

The sheet feeding device is operated from the same mechanisms as those which operate the other portions of the machine. In the present instance a bracket 19 is provided having bearings 20 and 21 in which a shaft 22 is journaled having a flywheel 23 freely rotatable thereon in which there is a groove 24 in which a belt or the like may be arranged that will be directed to a suitable source of power such as an electric motor. The flywheel 23 is connected to the shaft 22 by the clutch structure 25 fully described and claimed in my referred to co-pending application, Serial No. 497,439 and more fully described hereinafter. Also freely mounted on the shaft 22 is a spur gear 26 connectable to the shaft by the clutch structure 27. The gear 26 meshes with a gear 28, freely rotatable on the shaft 29 and connected to a spur gear 30 by the sleeve 31. The spur gear 30 meshes with a pinion 32 (Fig. 10) fixed on the shaft 33 extended to the front of the machine into a gear housing 34 in which a speed changing mechanism is provided, as described in my referred to co-pending applications, Serial No. 497,438 and Serial No. 497,439. The shaft 29 is suitably journaled and is extended to and is driven from the mechanisms comprising the speed changing device. Fixed on the shaft 29 is a bevel gear 36 meshed with a bevel gear 37 mounted on the cam shaft 38 suitably journaled and extended across the machine above the table top 14.

The sheet feeding devices include the belt 16 extended across the machine above and in juxtaposition to the table top 14 and it is directed around pulleys, such as 41, mounted on shafts 39 and 40 suitably journaled at opposite ends of the machine. The belt 16 is endless and is directed below the table top 14 and around suitable guide pulleys 42 (Fig. 10) carried by brackets 43 mounted on the frame 12. The shafts 39 and 40 are interconnected by an endless belt 44 directed about pulleys mounted thereon and therefore the shafts 39 and 40 will be synchronically operated. In the present instance it is the shaft 39 which is driven and the drive includes the pinion 45 (Fig. 10) fixed on the shaft 39 and meshed with

an intermediate gear 46 meshed with the pinion 32. It is apparent that the shaft 39 will be operated rapidly relative to the operation of the shaft 22 by reason of the ratio between the gears 30 and 32. The belt 16 is operated to move toward the right in Fig. 10, which will be toward the left in Fig. 1, and the devices for withdrawing the sheet from the storage rack are arranged to direct the sheet onto the belt 16 adjacent the shaft 39.

As has been stated, the platen P is operated from the shaft 17 and this shaft is driven by the bevel gear 47 meshed with the bevel gear 48 mounted at the inner end of the shaft 22. Since all the mechanisms are driven from the shaft 22 it is manifest that timed relation therebetween may be maintained by arranging the various power transmitting parts to be of a predetermined ratio and therefore the cam shaft 38 may be arranged to operate in predetermined relation with the shaft 17, and this rotation of the cam shaft 38 is determined by the number of sections on the tax bill to be printed. Thus, if the tax bill embodies two sections the shaft 17 will be rotated twice to one revolution of the cam shaft 38 and if a three section tax bill is to be printed then the machine would be so arranged that the shaft 17 would make three revolutions to one of the cam shaft 38.

The mechanisms for withdrawing the sheets from the storage rack are best illustrated in Figs. 2, 5, 6, and 11, and by referring thereto it may be seen that a sucker bar 49 is rockably mounted in a suitable manner on the frame 12, and this sucker bar extends transversely of the machine in juxtaposition to the upper end of the rack 50 and is disposed at the end of the machine at which the shaft 39 is journaled. In this rack the sheets or bills S are stacked in vertical disposition and as best shown in Fig. 6 the upper edges of these sheets extend beyond the upper end of the rack 50. On the sucker bar 49 are a plurality of nozzles 51 arranged in spaced relation. These nozzles are movable into a position to engage the sheet resting against the substantially vertically extending plate of the rack.

It has been pointed out that the sucker bar is rockably mounted and provided thereon is a depending boss 52 to which one end of a link 53 is pivotally connected and at the opposite end of the link 53 is a rotatably mounted roller 54 engaging the peripheral cam 55 fixed to the shaft 35 and rotatable in the direction of the arrow shown on Fig. 6. When the roller 54 is engaging the rise on the cam 55 the sucker bar 49 is so positioned that the nozzles 51 are located slightly downwardly of the position illustrated in Fig. 11, which will be described more fully hereinafter. However, when the roller moves into the depression in the periphery of the cam 55 the sucker bar 49 is pivoted upwardly and the nozzles 51 engage the inwardmost sheet.

The sucker bar 49 is hollow and one end thereof is tightly closed while to the other end a suitable conduit is connected which is directed to an air exhausting means (not shown) of approved form which may be an air pump, blower or the like and the conduit extending from the sucker bar 49 is connected to the inlet of such air exhausting means and air is therefore drawn through the nozzles 51. Thus, when the nozzles 51 engage the inwardmost sheet, passage thereto is closed by the sheet and a vacuum is drawn in the sucker bar 49 and nozzles 51 and therefore the sheet is tightly held against the nozzles. The cam 55 will continue to rotate and

the roller 54 will move into engagement with the intermediate portion of the cam, as illustrated in Fig. 11, and when in this position the sucker bar 49 and the nozzles 51 are pivoted into position 5 substantially similar to that illustrated in Fig. 11.

It has been pointed out that the shaft 33 is operated rapidly relative to the speed of rotation of the shafts 22 and 29 and adjustably mounted on the shaft 33 are feed rollers 56, 56 which are 10 secured thereto by set screws or the like in order that they may be positioned near the center of the sheet to be fed into the machine. The nozzles 51 move so as to pass below the periphery of the feed rollers 56, as shown in Fig. 11, and the 15 feed rollers 56 are rotated with the shaft 33 in the direction of the arrow in Fig. 6 and therefore when the nozzles 51 move below the periphery thereof of the sheet, held thereagainst by the vacuum in the sucker bar 49, will engage the peripheries of the feed rollers 56.

The sheets are forced into engagement with the periphery of the feed rollers 56 by the clamping rollers 57, 57 in the form of ball bearings and adjustable along the shaft 58 on which they are 20 mounted so that they may be aligned with the feed rollers 56, 56. The shaft 58 is carried by arms 59 (Fig. 6) of the bell crank levers pivotally mounted at 60 on the arms 61 pivotally mounted on the shaft 33. At the outer end of one of the 25 arms 61 is a roller 62 engaging the peripheral cam 63 fixed on the shaft 35, and when the roller 62 is engaging the drop on the cam the shaft 58 is so positioned that the rollers 57 engage the feed rollers 56, forwardly of a vertical center 30 plane through the shaft 33 in an appreciable amount, as illustrated in Fig. 11, said rollers 57 being held in engagement with the rollers 56 by a spring 64 extended between spring anchors in the arms 59 and spring anchors in the bracket 65. 35 However, when the roller 62 engages the rise on the cam 63 the arm 61 will be moved toward the right into the position shown in Fig. 6 and therefore the rollers 57 will be moved toward the vertical center plane through the shaft 33 to 40 permit the upper edge of the sheet being moved by the nozzles 51 to pass the rollers 57 and into engagement with the rollers 56, and as soon as the roller 62 moves from the rise on the cam 63, which will immediately follow the just described 45 movement of the nozzles 51 below the peripheries of the rollers 56, the rollers 57 will move over the sheet and therefore very effectively clamp the same against the feed rollers 56 and at this time the vacuum in the sucker bar 49 will be broken in a manner to be described and therefore the 50 sheet will be rapidly fed by rollers 56 onto the sheet moving means which in the present instance is the belt 16.

It is important that the rollers 57 move toward 55 the vertical center plane through the shaft 33 sufficiently to permit the edge of the sheet to pass thereby, but by reason of the fact that the clamping rollers 57 must quickly move into position to clamp the sheet against the feed rollers 56, it is 60 necessary that this positioning of the rollers 57 out of the path of the edge of the sheet be nicely adjusted. Legs 66 (Fig. 6), forming a part of the bell crank levers embodying the arms 59, are engaged with a bar 67 supported by screws such as 65 68 mounted in the bracket 65 and therefore the position of the rollers 57 radially of the rollers 56 may be varied to afford proper clamping of sheets of varied thickness. By varying the position of these screws the position of the arm 59 70 may be adjusted which will manifestly vary the

position of the rollers 57 on the peripheries of the feed rollers 56.

An arm 69 (Fig. 11) is pivotally connected to the upper end of the link 53 at the rotatable mounting of the roller 54 and this arm is also pivotally mounted on the frame at 70. A spring 71 extends between spring anchors on the arm 69 and the frame and urges the roller 54 into engagement with the cam 55.

It has been pointed out that the cam 55 embodies, in addition to the rise and fall thereof, an intermediate portion and the roller 54 is shown on this intermediate portion in Fig. 11, and as the roller 54 moves from this intermediate portion onto the dwell an additional movement is imparted to the link 63 and the arm 69 to break the vacuum in the sucker bar 49. The means enabling this include the block 71' mounted on the sucker bar 49 and having pivotally mounted thereon at 72 a bell crank 73 including 10 an arm 74 having an adjusting screw 75 therein engaging the block 71' whereby the disposition of the arm 76 of the bell crank 73 may be varied. The arm 76 normally rests against the head of the stem 77 of the poppet valve including the valve disc 78 normally closing a plurality of openings communicating with the hollow interior of the sucker bar 49. A spring 79 acts on the head of the stem 77 to normally hold the disc 78 in closing position. However, at the time the roller 54 15 moves from the intermediate portion of the cam 55 onto the rise or dwell thereof, movement is imparted to the arm 69 which is transmitted through the block 71' and arm 76 of the bell crank 73 to act on the stem 77 against the effect 20 of the spring 79 to move the disc 78 from closing position relative to the openings communicating with the sucker bar 49, and as soon as passage is permitted through these openings, the vacuum in the sucker bar 49 is destroyed and this occurs 25 simultaneously with the clamping of the sheet against the feed rollers 56 by the clamping rollers 57. As the cam 55 continues to rotate, the nozzles 51 are moved below the position illustrated 30 in Fig. 11, and are out of the way of the sheet 35 which may then be unrestrictedly fed by the feed rollers 55 in the above described manner.

Another cam 80 is fixed on the shaft 35 and a roller 81 (Fig. 6) is held thereagainst by the spring 82. The roller 81 is carried by the arm 83 and one end of the spring 82 is connected to a stud on this arm. The other end of the arm 83 is mounted on the pivotal mounting 70 and connected therewith is the finger arm 84, carrying the finger bar 85. After the nozzles 51 have 55 moved the inwardmost sheet downwardly and substantially into engagement with the feed rollers 56, the cam 80 will have rotated in an amount sufficient to engage the roller 81 with the rise thereon and at this time the finger bar 60 85 will have been moved into engagement with the sheets in the rack 50 to hold the sheets therein as the sheet engaged with the nozzles 51 is withdrawn from the rack. The finger bar 85 moves into engagement with the sheets in the 65 rack 50 as soon as the sheet held against the nozzles 51 moves thereby. In this manner displacement of the other sheets from the rack is prevented during the removal of the sheet to be fed into the machine.

The speed changing mechanisms in the housing 34 operate the shaft 35 in timed relation with the platen operating shaft and if a two section tax bill is being printed the platen operating shaft will make two revolutions to one of shaft 35. 70 75

Therefore, if the sheet being printed is a tax bill for real property and the legal description of the parcel of real property is arranged on but a single printing device, a sheet will be fed into the machine in the above described manner and two impressions will be made thereon and the sheet will then move from the machine and a new sheet will be fed thereinto. If, for example, this new sheet is to receive four impressions, as when the 5 legal description for a parcel of real property is arranged on a lead and one follower printing device, four impressions will be made on the sheet, two impressions being made from the lead printing device and two impressions will be made 10 from the follower printing device. The sheet is shifted in the manner described heretofore and with particularity in my co-pending application Serial No. 497,439, at the time the follower printing device supplants the lead printing device at 15 printing position in the machine and during this time, it is necessary that the sheet feeding mechanism be held against operation in order that a new sheet will not be fed into the machine until 20 all of the impressions have been made on the previous sheet.

To this end, a boss 86 is provided on the sucker bar 49 and an arm 87 is provided, the outer end of which is engageable with the boss or lug 86, for a purpose and in a manner to be described. A 25 bracket 88 is mounted on the frame of the machine and carries a solenoid 89 including an armature 90. An arm 91 is provided on the bracket 88 and the arm 87 is pivotally mounted thereon at 92. An adjustable screw 93 is carried by 30 the arm 87 and normally rests against the armature 90 to hold the outer end of the arm 87 in the path of movement of the lug 86 when the sucker bar 49 is moved in the previously described manner. However, when the solenoid 89 is energized, the armature 90 thereof acts to withdraw the arm 87 from the path of movement of the lug 86. When the solenoid is not energized the arm 87 remains in position to be engaged by the lug 86 and this prevents the sucker bar 49 from 35 moving to engage the nozzles 51 with the inward-most sheet in the rack 50.

The solenoid 89 is energized at a predetermined time in the operation of the machine and this is controlled by the timing switch 94 (Fig. 4), 40 operable by the pin 95 on the disc 96 mounted on the cam shaft 38.

On the printing devices from which the impressions are taken, variable members are provided in the form of tabs or the like and these members are utilized to bring about the interruption of the feeding mechanism by engaging the arm 87 with the lug 88 in the manner described. These members are indicated by T in 45 Fig. 12 and are provided on all of the printing devices preceding a lead printing device, for when a lead printing device is to move into printing position and a new sheet is to be fed into the machine this feeding of a new sheet follows the making of the last impression on the previously 50 fed sheet. These tabs T engage a rod 95 extended through a block of insulating material 96, and the insulated lower end of this rod engages a yieldable contact arm 97 on which there is a contact 98 engageable with a contact 99 on the yieldable contact arm 100. When the tab T depresses the rod 95 the contacts 98 and 99 are engaged but circuit is not closed to the solenoid 89 until the timing switch 94 is closed. Circuit is closed 55 to the solenoid 89 from the line wires 101 and 102 when the switches 103 and 104 are closed, the

switch 103 being the main control switch of the machine, while the switch 104 is used to control the operation of the sheet feeding mechanism, and when this switch is open sheets will be 60 consecutively fed into the machine in accordance with the timing of the shaft 35, the arm at this time being manually thrown into an inoperative position. When the switches 103 and 104 are 65 closed current will flow from the line wires 101 and 102 into conductors 105 and 106 to energize the motor 107 which is the source of power previously referred to. Conductors 108 and 109 are 70 respectively connected to the conductors 105 and 106 and current therefore flows from the conductor 101 through the conductor 105, conductor 108, conductor 110 to contact arm 97 and when the contacts 98 and 99 are engaged current flows 75 therethrough into contact arm 100 through conductor 111 and when the switch 94 is closed current flows through conductor 112, through the winding of the solenoid 89 through conductor 113, conductor 109, conductor 106 to conductor 102. Since the members T may be provided on as many 80 printing devices as required, it is manifest that the sheet feeding mechanisms may be rendered 85 inoperative for any required period and therefore, if the sheet fed into the machine is to receive four impressions this circuit will be opened to prevent the feeding of a new sheet until all four impressions have been made on the previously 90 fed sheet. If, by way of example, the tax bills embody three sections and impressions are to be made from a lead printing device and two follower printing devices, nine impressions would be made on the sheet and therefore a new sheet 95 would not be fed until all nine impressions had been made.

In my co-pending application, Serial No. 497,438, I have described the manner in which the clutch 25 is engaged so that the shaft 22 will be 40 driven with the flywheel 23. In the event no sheet is fed into the machine because of a failure of the sheet feeding mechanism, a safety device is provided which will disengage the clutch 25 to thus disconnect the shaft 22 from the flywheel 45 23 and, as the various mechanisms in the machine are driven from the shaft 22, it is manifest that operation thereof will therefore be interrupted. This safety mechanism includes a grooved pulley 114 mounted on the shaft 39 adjacent the pulley 41. Depending from the bracket 19 is a lug 115 on which an arm 116 is pivotally mounted. The arm 116 carries a shaft 117 on which a roller 118 is rotatably mounted, said roller being aligned with the groove in the pulley 50 114. If a sheet S is fed into the machine the sheet will be disposed between the roller 118 and the grooved pulley 114, as illustrated in Fig. 9, and the parts will therefore be held in the positions illustrated in Figs. 7 and 9. However, should 55 no sheet be fed into the machine, the roller 119 at the outer end of the arm 116, will move into the fall in the cam 120 fixed on the shaft 35, said roller being held from said fall when the roller 118 rides on the sheet as illustrated in Fig. 9. 60 When the roller moves into the fall in the cam 120 the link 121 is permitted to move downwardly, said link normally being held in an upper position by a lug on the arm 116, which arm is held in upper position by the roller 118 riding on 65 the rise on the cam 120. When the link 121 pivots downwardly the nose 122 thereof engages the shoulder 123 on the cam 124 fixed on the shaft 35. The mechanisms for holding the clutch engaged 70 include the latching member 125 and the dog 126. 75

said plate and dog having shoulders 286 and 287 which are normally engaged, as illustrated in Fig. 7, but when the nose 122 engages the shoulder 123 a movement is imparted through the link 121

5 which pivots the plate 125 and disengages the shoulders on said plate and the dog 126 and the shoulders move into the position illustrated in Fig. 8 which causes disengagement of the clutch 25.

10 The clutch 25 includes a collar (Fig. 14) which is suitably secured to the flywheel 23 but which is rotatable on shaft 22. A disc 292 is fixed to the shaft 22 and pivotally mounted on this disc is a latching pawl 293 having a nose 294 which is urged toward a pocket 295 in the collar 291 by a spring 296, said nose being held out of said pocket by the engagement of the pawl with the latching member 297 which is pivotally mounted at 298 on the frame of the machine and which has a pin 299 therein. The member 301 fixed on shaft 289 has a slot 300 therein which is eccentric to the shaft 299. When the handle 290 is disposed, as shown in Fig. 7, the member 301 is so positioned that the pin 299 is in the less eccentric portion of the 15 slot 300 and the nose of the latching member 297 is drawn from engagement with the pawl 293 and the nose 294 thereof is seated in the pocket 295 and thus the flywheel 23 and the shaft 22 are connected. When, however, the handle 290 is so 20 moved as to move the rounded portion 302 of the dog 126 into engagement with the latching member 125, as shown in Fig. 8 the latching member 297 engages the pawl 293 and disengages the nose 294 from the pocket 295 and thus the flywheel is 25 disconnected from the shaft 22. The latching member 125 is urged toward the dog 126 by the spring 303 but the rounded portion 302 prevents engagement until the handle 290 has been moved to properly position the shoulder 287. The movement imparted to the rod 122 is in opposition to 30 the action of the spring 303 and it is therefore manifest that the rod will disconnect the shoulders 286 and 287 which are normally engaged and the spring 303 acts through the shaft 289 to urge 35 the handle 290 into a position whereat the rounded portion 302 will be engaging the latch 125. The disengagement of the shoulders 286 and 287 may also be brought about by the safety handle 304, the striking of this handle obviously disengaging 40 the shoulders.

45 In the foregoing description I have set forth my invention in connection with a printing machine used in the printing of tax bills but this is not to be taken as a limitation of my invention for it is susceptible to many other uses other than in the printing of tax bills. It is however manifest that I have provided a device which will readily operate to interrupt the operation of the sheet feeding mechanism in order that a plurality of 50 impressions may be made on a sheet being printed without destroying the timed relation of the sheet feeding mechanism with the other mechanisms of the machine. Moreover, I have provided a device wherein the sheet feeding mechanism may be interrupted in a variable manner so that a predetermined number of impressions may be made on one sheet, while a different number of impressions may be made on another sheet and, if desired, still a greater or less number of 55 impressions may be made on a third sheet and the device is so constructed that a new sheet will be fed into the machine when the last of the impressions have been made on the previously fed sheet. Moreover, the device is so constructed that 60 operation of the machine will be interrupted in 65

the event no sheet is fed thereinto and this augments the maintenance of the timed relation between the various devices on the printing machine and the sheet feeding mechanism.

70 In the foregoing description I have disclosed a selected embodiment of my invention but it is to be understood that this is capable of variation and modification and I therefore do not wish to be limited to the precise details but desire to avail myself of such changes and modifications as fall 10 within the purview of the following claims:

I claim:

1. In a printing machine which has printing means and means for controlling the operation thereof whereby a variable number of impressions may be made on a sheet fed into the machine, sheet feeding means, and means controlling the operation of said sheet feeding means and including a part which is in operative position when the last impression is being made on a sheet and another part operating in timed relation with the printing means and cooperating with the first part to delay feeding of a new sheet into the machine until the last impression has been made on a previously fed sheet. 15

2. In a printing machine which has printing means and means for controlling the operation thereof whereby a variable number of impressions may be made on a sheet fed into the machine, sheet feeding means, and electrical means controlling the operation of the sheet feeding means and including a switch which is closed when the last impression is being made on a sheet and another switch in series with the first switch and operating in timed relation with the printing means to delay feeding of a new sheet into the machine until the last impression has been made on a previously fed sheet. 20

3. In a printing machine which has printing means and means for controlling the operation thereof whereby a variable number of impressions may be made on a sheet fed into the machine, sheet feeding means, and electrical means embodying a switch closed by the printing means when the last impression is being made on a sheet and another switch in series with the first switch and operated in timed relation with the printing means to delay feeding of a new sheet into the machine until the last impression has been made on a previously fed sheet. 25

4. In a printing machine which has printing means and means for controlling the operation thereof whereby a variable number of impressions may be made on a sheet fed into the machine, means for positioning the sheet relative to the printing means and including a part operating in timed relation with the printing means, sheet feeding means, means controlling the operation of the sheet feeding means whereby a sheet is not fed into the machine until the last impression has been made on the preceding sheet, and means regulating the operation of the controlling means and controlled by means associated with the printing means and said part of said sheet positioning means. 30

5. In a printing machine which has printing means and means for controlling the operation thereof whereby a variable number of impressions may be made on a sheet fed into the machine, means for positioning the sheet relative to the printing means and including a part operating in timed relation with the printing means, sheet feeding means, means including electro-magnetic means for controlling the operation of 35

the sheet feeding means whereby a sheet is not fed into the machine until the last impression has been made on the preceding sheet, and an electric circuit for regulating the operation of the controlling means and including switch means operated by means associated with the printing means and said part of said sheet positioning means.

6. In a printing machine which has printing means and means for controlling the operation thereof whereby a variable number of impressions may be made on a sheet fed into the machine, means for positioning the sheet relative to the printing means and including a part operating in timed relation with the printing means, sheet feeding means, electro-magnetic means for controlling the operation of the sheet feeding means whereby a sheet is not fed into the machine until the last impression has been made on the preceding sheet, and switch means controlling the operation of said electro-magnetic means and including a part operated by the printing means and another part operated by said part of said sheet positioning means to operate said controlling means at a predetermined time in the operation of the machine if the part controlled by the printing means is rendered operative.

7. In a printing machine which has means for sequentially moving variable printing devices therethrough, a platen for making impressions from said printing devices, means for controlling the operation of said printing device moving means whereby a variable number of impressions may be made on sheets fed into the machine, sheet feeding means, and electrical means controlling the operation of the sheet feeding means and including a switch operated by control means on the printing devices and another switch in series with the first switch and operated in timed relation with the platen to delay feeding of a new sheet into the machine until the last impression has been made on a previously fed sheet.

8. In a printing machine which has means for sequentially moving variable printing devices therethrough, a platen for making impressions from said printing devices, and means for controlling the operation of said printing device moving means whereby a variable number of impressions may be made on sheets fed into said machine by the platen from the printing devices, the combination of a sheet feeding means including a rack for supporting the sheets to be printed in the machine, a feed roller, suction means for withdrawing a sheet from the rack and moving it into engagement with the feed roller, a clamping roller, means for retracting the clamping roller to permit engagement of a sheet with the feed roller and for advancing the clamping roller into position to clamp the sheet in engagement with the feed roller, means for rendering said suction operated means inoperative when the sheet is engaged with said feed roller, and means for delaying the operation of the sheet feeding means until the last impression has been made on a sheet previously fed into the machine.

9. In a printing machine which has means for sequentially moving variable printing devices therethrough, a platen for making impressions from said printing devices, and means for controlling the operation of said printing device moving means whereby a variable number of impressions may be made on sheets fed into said machine by the platen from the printing devices,

the combination of a sheet feeding means including a rack for supporting the sheets to be printed in the machine, a feed roller, suction nozzles, means for moving said suction nozzles into engagement with the forwardmost sheet in the rack and for then moving said nozzles past the periphery of the feed roller to engage the sheet with the feed roller, a clamping roller, means for retracting the clamping roller to permit engagement of the sheet with the feed roller and for advancing the clamping roller into position to clamp the sheet in engagement with the feed roller, means for rendering said suction operated means inoperative subsequent to movement thereof past the periphery of the feed roller and subsequent to advancing of the clamping roller, and means for delaying the operation of the sheet feeding means until the last impression has been made on a sheet previously fed into the machine.

10. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, and suction operated means for withdrawing a sheet from said sheet supporting means when the last of the variable number of impressions have been made on a sheet previously fed into said machine.

11. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, suction operated means for withdrawing sheets from said supporting means when the last of the variable number of impressions have been made on a previously fed sheet, and means for moving the withdrawn sheet into said printing machine.

12. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing sheets from said supporting means when the last of the variable number of impressions have been made on a previously fed sheet, means for moving the withdrawn sheet into said printing machine, and means for clamping the withdrawn sheet in engagement with the moving means.

13. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for with-

drawing sheets from said supporting means when the last of the variable number of impressions have been made on a previously fed sheet, means for moving the withdrawn sheet into said printing machine, means for clamping the withdrawn sheet in engagement with the moving means, and means for withdrawing said clamping means to permit a sheet to pass thereby and for moving said clamping means into clamping position after 10 a sheet has passed thereby and engaged said moving means.

14. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing sheets from said supporting means when the last of the variable number of impressions have been made on a previously fed sheet, means 20 for moving the withdrawn sheet into said printing machine, means for clamping the withdrawn sheet in engagement with the moving means, means for withdrawing said clamping means to permit a sheet to pass thereby and for moving 25 said clamping means into clamping position after a sheet has passed thereby and engaged said moving means, and manually adjustable means for determining the position of said clamping means on said moving means.

15. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing a sheet from said sheet supporting means when the last of the variable number of impressions have been made on a sheet previously fed into said machine, and means for holding the remaining sheets in said supporting means as said 35 withdrawing means moves a sheet therefrom.

16. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing a sheet from said sheet supporting means, and means for controlling operation of said withdrawing means whereby a new sheet will not be fed into the machine until the last of the 40 variable number of impressions have been made on a previously fed sheet.

17. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means

including sheet supporting means, means for withdrawing a sheet from said sheet supporting means, means for controlling operation of said withdrawing means whereby a new sheet will not be fed into the machine until the last of the variable number of impressions have been made on a previously fed sheet, and electrically operated means for controlling the operation of said controlling means.

18. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing a sheet from said sheet supporting means, means for controlling operation of said withdrawing means whereby a new sheet will not be fed into the machine until the last of the variable number of impressions have been made on a previously fed sheet, electrically operated 20 means for controlling the operation of said controlling means, and means operating in timed relation with said platen for controlling the operation of said electrically operated means.

19. In a printing machine which has means for sequentially moving variable printing devices therethrough, a platen for making impressions from said printing devices, and means for controlling the operation of said printing device moving means whereby a variable number of impressions may be made on the sheets fed into said machine by said platen from said printing devices, the combination of sheet feeding means including sheet supporting means, means for withdrawing a sheet from said sheet supporting means, means for controlling operation of said withdrawing means whereby a new sheet will not be fed into the machine until the last of the variable number of impressions have been made on a previously fed sheet, electrically operated 30 means for controlling the operation of said controlling means, and means operating in timed relation with said platen for controlling the operation of said electrically operated means.
